UNITED STATES PATENT OFFICE

HARRY O. SECREST, OF CLEVELAND, OHIO; HAROLD K. BAUMGARDNER AND MYRA O. SECREST, ADMINISTRATORS OF SAID HARRY O. SECREST, DECEASED, ASSIGNORS TO THE SECREST SAFETY RAZOR CORPORATION, OF CLEVELAND, OHIO, A CORPORATION OF OHIO

SAFETY RAZOR

Application filed October 26, 1928. Serial No. 315,199.

The invention disclosed herein relates to safety razors.

The object of the invention is to provide a safety razor including improved blade holding means for holding the blade in the proper position for either shaving or honing, together with a handle removably secured to the blade holder in various positions whereby the position of the cutting edge with respect to the handle may be varied to meet the desires or requirements of the user and at the same time permit an arrangement of the holder in such a position that the blade may be conveniently honed or sharpened.

The foregoing features of the invention as well as the various details will be brought out in the following description, drawings and claims.

Referring to the drawings, Fig. 1 is a plan view of the razor; Fig. 2 is a bottom plan of the blade holder end; Fig. 3 is a section upon the line 3—3 of Fig. 1; Fig. 4 is a bottom plan view of the holder with the blade secured in position ready for honing; Fig. 5 is a side view of the handle and holder with the guard and blade removed; Fig. 6 is a composite view of the guard and blade separated; Fig. 7 is a section upon the line 7—7 of Fig. 1, showing the guard and blade clamped in position in the holder; Fig. 8 is a similar view with the clamping device in released position with the blade and guard removed; Fig. 9 is a similar section showing the blade alone clamped for honing; Fig. 10 is a bottom plan view showing another type of clamp; and Fig. 11 is a section upon the line 11—11 of Fig. 10.

In the embodiment of the invention set forth in the drawings, 1 represents a suitable handle threaded at 2 and made of any suitable shape so that it is handy for use by the operator.

Cooperating with the handle is a blade holder of generally U-shaped plate form con-

sisting of the body portion 3 connected by a back bend 4 to a backing plate 5 against which the blade is clamped. The outer edges of the plates are preferably curved, and the backing plate projects beyond the body plate being provided beyond its edge with an inwardly projecting bead 6 for engagement with the blade, as will appear. The U-shaped structure of this holder is re-enforced by suitable ribs 7 which extend around the back bend 4 and for a considerable distance toward the edges of the plate portions 3 and 5.

The mounting between the holder and the handle is provided by shearing a tongue 8 from the body portion 3 adjacent the back bend 4 and bending it outwardly from the back bend to form a boss having an opening for receiving a rivet 9 passing through the two legs 10 and 11 of an inserted eye 12. This eye is threaded to receive the threaded portion 2 of the handle. The threads extend through the eye parallel with the blade, so that the handle may be applied in either of two positions, as indicated in Fig. 1, so that the blade holder and blade may be presented to the face in what might be termed right and left side cutting positions with respect to the handle, as in the case of the old-fashioned razor. In order to mount the holder and handle in a position corresponding to well known hoe type safety razors, the body plate 3 is pressed out to provide a hollow boss 13 having a threaded opening 14 for receiving the handle, as in Fig. 5. With the parts so connected, the plane of the blade is at an angle to the axis of the handle but crosses it. Between the boss 13 and the eye 12 is located a suitable clamping device for the blade along or for the blade and guard, according to whether the device is used for honing or stropping or for shaving.

The clamping device shown in Fig. 1 comprises a lever 18 mounted to turn on a rivet 16 between a wall 15 of the boss 13 and a lug 17 of the eye 12, said lever having a finger 90

piece 19 and opposed cam lobes 20 and 21, the former having less pitch than the latter and being used for holding the guard and blade in place, as will appear, while the higher lobe 5 21 is used for clamping the blade alone, as will be described. From the drawings, it will be seen that the lever may be swung through 180° and when it is at 90° or in mid-position it is in release or non-clamping position 10, as shown in Figs. 7, 8 and 9.

As before suggested, the holder is arranged to receive and firmly clamp either the blade and guard together or the blade alone, and the blade and guard will now be described. 15 The guard is partially shown in bottom plan in Fig. 1; in top plan in Fig. 2; in section in Fig. 3 and in edge view in Fig. 6. It comprises a main plate portion 22 of substantially the shape of the clamping plate but slightly 20 wider and slightly longer. At its lateral edges it is provided with upwardly extending teats 23 struck out from the metal and adapted to register with or enter recesses 32 in the blade ends for alining or positioning the blade 25 and guard, and which teats also ride in guiding recesses 33 along the edges of the backing plate 5 to center the assembled guard and blade in the holder and guide them to place when assembling the parts for use. The forward edge of the guard is made to conform 30 with the free edge of the clamping member in that it has the same curved shape. It is also provided with a plurality of notches 24 forming the usual guarding teeth or comb. 35 The guard is also provided at the ends of its comb portion with outwardly extending angular extensions 25, each provided with a corner guard teat 26 struck up from the metal of the plate at these points and which guard 40 or shield the face from the sharp corners of the blade. Within the outer toothed edge the plate is depressed on its blade side to form a groove 27 and within the same is again depressed in the opposite direction to form a 45 ridge 28. When the blade is in place its cutting edge lies just within the free ends of the guard teeth and beyond the groove 27, and the rib 28 is just within the bead 6. Within the rib 28 the guard plate has another rib 29 50 on its opposite face upon which the edge of the body plate rides as the guard and blade are pushed to home position, its purpose being to slightly flex the blade against the bead 6 and cause its cutting edge to hug the guard 55 teeth.

The blade comprises a plate 30 having a curved cutting edge 31 and edge recesses 32 adapted to receive the lateral teats 23. It is reversible, face for face. When the blade is 60 assembled upon the guard the two, as an assembly unit, may be inserted in the holder by sliding them between the body and backing plates, the teats 23 guiding the parts to position by riding in the recesses 33 of the 65 backing plate. The shoulders at the ends

of the recesses 33 provide stops to limit the inner movement of the blade and guard assembly. When the guard and blade are assembled the outer corners of the blade are protected by the teats 26. 70

In using the razor, assuming that the blade and guard are in position, the operator may insert the handle in either end of the eye 12 and use it as he sees fit. If he desires the hoe action of the ordinary safety razor he 75 may place the handle in the threaded opening 14. In placing a blade in the razor, the clamping device is moved to the release position and both the blade and guard are drawn out. The new blade is then laid upon the 80 guard plate, the notches in the sides of the blade engaging the teats 23 and the corners of the blade lying behind the teats 26. These parts, forming the blade-guard assembly, may be slid into the holder, whereupon the 85 clamping device is moved to the clamping position shown in Fig. 7, when the razor is assembled and ready for shaving use.

When honing or stropping the blade, the operator places the handle in one of the two 90 positions shown in Fig. 1 and removes the blade and guard assembly. He then replaces the blade alone, as shown in Fig. 4, and moves the clamping device to the second clamping position, shown in Fig. 9, when the 95 blade will be firmly held in place and may be sharpened on a hone, strop or other means.

In the modified form of holder shown in Fig. 10, the body plate is provided with a clamping screw 35 provided with a rounded 100 nose 36 for engaging the guard and blade as an assembly, or the blade alone. The screw is also provided with a suitable rigid operating handle 37 having a suitable flat finger piece 38. The screw is threaded into an 105 opening which lies between the raised boss 13 and one of the legs 11 of the eye to which the handle is attached. Its threads are rather coarse pitch so that in a little more than 180° of rotation, which is its limit of movement, it 110 has the necessary longitudinal advance to not only either clamp the blade alone for honing or the blade and guard for shaving, but to also provide a little extra motion to compensate for the effect of wear on the end of the screw. 115 In other words, in the razor as originally constructed, the blade alone may be firmly clamped by rotation of the screw to a point short of its limit of movement, and as the end of the screw wears, additional screw rotation is possible within reasonable limits. Rotation of the screw 35 in opposite directions is limited by engagement of the lever 37 or its thumb piece 38 with the boss 13 into which the handle is threaded. The operating 120 lever 37 therefore lies in a sort of recess, as it were, below the level of the top of the boss 13. In practice the lever is secured to the screw so as to rotate therewith while the screw is threaded into its hole in the body portion. 130

As a result, it is actually permanently attached to the razor body and cannot escape therefrom because when rotated in the unscrewing direction, the lever 37 engages the boss 13 before the threads of the screw leave the threads of the opening into which they are threaded. This is a very simple construction and quite efficient for the purpose. The guard plate 22 is provided with a suitable depression 39 at its back central portion for receiving the rounded nose 36.

This modified type of razor is used in a manner quite similar to the other type in that the assembled guard and blade may be firmly clamped in place for the shaving operation and the blade alone may be firmly clamped in the holder for sharpening or honing. Nevertheless, as shown in Fig. 10, the device as a whole is quite flat and thin, with no appreciable projections either from the face of its body portion or the face of its backing, which projections otherwise might interfere with honing or stropping. A blade clamped in this holder may be applied to a hone at a much sharper or acute angle of inclination.

Having described my invention, I claim:

1. A blade holder for safety razors, comprising a U-shaped frame including a body plate and a backing plate connected by a back bend, the edge of the backing plate projecting beyond the edge of the body plate, and clamping means carried by one of said plates for holding the blade in place, comprising a pivoted lever having cam lobes, one of the lobes having greater height than the other.

2. A blade holder for safety razors, comprising a U-shaped frame including a body plate and a backing plate connected by a back bend, and handle securing means comprising a lug struck out from the back bend, a threaded eye having legs straddling said lug, a threaded handle receiving boss struck outwardly from the center of the body plate, and a blade clamping device located between said boss and said eye.

3. A safety razor, comprising a holder of the U-shaped frame type, including parallel spaced plates separated by a blade receiving cavity and connected by a back bend, the back bend intermediate its ends having an eye extending outwardly and provided with a relatively short opening presenting endwise and in opposite directions with their common axis parallel to the planes of said plates two alined handle receiving sockets located near the middle of the back bend, one of said plates at approximately its center having an opening presenting another handle receiving socket with its axis crossing the general plane of said plates.

4. A razor of the form described in claim 3, including clamping means located between the handle receiving opening in said plate and said eye.

5. A safety razor, comprising a U-shaped

frame including parallel plates separated by a cavity and connected by a back bend, reinforcing ribs extending along the plates and around the back bend, the back bend between said ribs being provided with an outwardly extending lug; a handle, and a pierced eye having legs straddling said lug and provided with a handle receiving opening having its axis in the plane of said cavity.

6. A razor of the form described in claim 5, including a blade and a plate-like guard having a comb edge to receive the edge of the blade, the plates bounding said cavity being separated sufficiently to receive between them both the blade and guard, clamping means permanently mounted upon one of the frame plates and having a range of clamping movement adapted to secure in said cavity either the blade alone or the blade and guard together, and one of said frame plates being provided with an opening whereby the handle may be also secured to the frame in a position approximately normal thereto.

7. A safety razor, comprising a U-shaped frame including parallel body and backing plates connected by a back bend, a guard member and a blade member adapted in superposed relation to be inserted between said plates, one of said members having a recess and the other member a projection, the recess and projection registering to maintain said members in definite relation to each other, and one of said plates having a recess to receive said projection for locating the assembled blade and guard members in proper position in the holder.

8. A safety razor, comprising a holder including parallel plates connected by a back bend, a guard member and a blade member adapted for insertion into position between said plates, one of said members having recesses and the other having projections to enter said recesses and aline said members relative to each other, one of said plates having a handle receiving opening, a handle therefore, and the other of said plates having recesses to receive said projections to thereby definitely locate the assembled guard and blade relative to the handle.

9. A razor of the form described in claim 8, in which the back bend is provided intermediate its ends with an eye having an opening presenting handle receiving sockets longitudinally in opposite directions in the plane of the blade, and one of said plates between said eye and the handle securing opening in said plate carrying clamping means having a range of clamping movement adapted for the blade alone or for the blade and guard together.

10. A razor, comprising a U-shaped frame including body and backing plates connected by a back bend, the edge of the backing plate projecting beyond the edge of the body plate, and a guard adapted for insertion between
